RENEWABLE DART TARGET

Ellis Traub, Worcester, Mass.

Application February 27, 1946, Serial No. 650,557

9 Claims. (Cl. 273—102.2)

1

This invention relates to targets for darts or the like, and more particularly to targets of the type having electrical means for indicating the accuracy of the various hits.

Targets of the electrically indicating type as heretofore constructed have been complicated and expensive to manufacture. Furthermore, various parts of the target panels have been permanently wired to the indicating devices, so that it has not been feasible or convenient to replace such panels when they have become disfigured or otherwise damaged by continued use.

It is accordingly one object of the invention to provide an indicating target which will be comparatively simple and inexpensive to manufacture.

It is a further object of the invention to provide an indicating target having a comparatively inexpensive target panel which may be readily and quickly replaced with a new panel when desired.

It is a further object of the invention to provide an improved dart-receiving panel for an indicating target, which will not damage the darts in any way, and which can be manufactured at a comparatively low cost.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts:

Fig. 1 is a front elevation of a target for darts;

Fig. 2 is a view similar to Fig. 1, but with the indicator panel and the target panel removed from the apparatus;

Fig. 3 is a section taken on the line 3—3 of Fig. 2;

Fig. 4 is a section taken on the line 4—4 of Fig. 2;

Fig. 5 is a section taken on the line 5—5 of Fig. 2;

Fig. 6 is a perspective view of the indicator panel;

Fig. 7 is a perspective view of the target panel;

Fig. 8 is a section, on an enlarged scale, taken on the line 8—8 of Fig. 7.

Fig. 9 is a fragmentary view of the back of the target panel;

Fig. 10 is a fragmentary section taken on the line 10—10 of Fig. 8;

Fig. 11 is a view similar to Fig. 8, but showing a slight modification; and

Fig. 12 is a side elevation of a dart.

2

The embodiment illustrated comprises a hollow rectangular frame 15 of a suitable material, such as wood, the height of the frame somewhat exceeding its width. The interior of the frame is divided into an upper compartment 16 and a lower compartment 17 by means of a transverse horizontal frame member 19 of wood or the like, the lower compartment being substantially square. To the back of the frame there is secured a vertical rectangular plate 20, preferably of metal, such as tin-plated sheet steel, which forms the rear wall of both the compartments. The upper compartment 16 is closed at the front by a rectangular panel 21, and the lower compartment 17 is closed at the front by a substantially square target panel 23. Both of these panels are readily removable, and for this purpose the frame 15 and the transverse member 19 are provided with grooves 24 (Figs. 3 and 4) which slidably receive the edges of the panels. The right hand member of the frame has a slot 25 (Fig. 4) in the plane of the grooves, so that the panels may be removed and replaced through this slot, as indicated by the broken lines at the right of Fig. 1. Preferably a transverse horizontal frame member 26 extends across the central portion of the lower compartment 17, with its front edge in a common plane with the rear edges of the grooves 24.

30 The upper panel 21 is preferably made of a comparatively soft material, such as cardboard, which will not damage a dart accidentally striking the panel, and it is sufficiently thick to prevent complete penetration by a dart. This panel is provided with a horizontal row of openings 27 (five being shown) which are covered by a sheet 28 of a suitable transparent or translucent material applied to the rear surface of the panel. This sheet is preferably of sufficient strength and thickness to prevent penetration or shattering by a poorly aimed dart, and it carries various numerals, which serve to indicate the scoring values of different areas of the target panel 23.

45 Within the upper compartment there is provided a series of electric lamp bulbs 30, one for each of the panel openings 27. Each bulb is mounted in a socket formed in an ear 31 struck up from the rear plate 20, the center contacts of the bulbs engaging metal contacts 32 mounted on the upper surface of the frame member 19. The bulbs 30 are preferably located slightly below the openings 27, so that they are protected from poorly aimed darts which might possibly penetrate the sheet 28. Each bulb is enclosed 50 by a wall 34 of inverted U-shape forming a small

chamber in registration with the corresponding opening 27. These walls 34 may be conveniently made from a single strip of tin-plated sheet steel, suitably secured to the frame member 19. It will be apparent that the walls 34 not only confine the light from each bulb to the corresponding opening 27, but they also serve as light reflectors. In addition to the lamp bulbs 30, there is provided a further electrical signal in the form of a buzzer or bell 35 (Fig. 2) mounted on the plate 20 within the lower compartment 17, with one of its terminals 36 connected to the said plate.

The various signals are energized in accordance with the location of darts which penetrate the target panel 23. For this purpose a horizontal strip 37 of insulating material is mounted on the rear plate 20 adjacent the cross-member 26. On this strip 37 there are mounted five spring contacts 38, a spring contact 39, and a spring contact 40. The contacts are all made from thin yieldable sheet metal, and as shown in Fig. 4 they project (when free) slightly in front of the member 26. The contacts 38 are respectively connected to the five contacts 32 by means of insulated wires 42, and the contact 39 is connected to the terminal 43 of the buzzer 35 by an insulated wire 44. The contact 40 is connected by an insulated wire 46 to a spring contact 47 mounted on the lower cross-member of the frame 15. Electrical energy for operation of the indicating system is provided by a pair of dry cell batteries 49 mounted in end-to-end or series arrangement and supported by clips 50 struck up from the rear plate 20. The base of one battery engages the contact 47, while the central terminal of the other battery engages a contact 51 struck up from the rear plate 20. Obviously, a low voltage transformer or other suitable source of low voltage current may be used in place of the batteries. It will be clear that if the contact 40 is connected by some means to the contact 39, a circuit will be completed to energize the buzzer 35, and if the contact 40 is connected by some means to one of the contacts 38, a circuit will be completed to energize the corresponding bulb 30. Such completion of circuits is brought about by the metal point of a dart in conjunction with the target panel 23, as will now be described.

As shown in Figs. 1 and 7, the front surface of the panel 23 is printed or otherwise marked with a central circle or bull's-eye 53 surrounded by five substantially contiguous circular bands 54, which may carry different scoring indicia. The bull's-eye 53 and bands 54 form definite target areas, which preferably are colored in a contrasting manner, as indicated by the line shading on the drawings. While this circular arrangement of target areas is preferred, other shapes and arrangements may be employed if desired.

Referring now to Fig. 8, it will be seen that the target panel 23 is a laminated structure with several different layers. The front surface of the panel, on which the target areas 53 and 54 appear, is formed by a sheet 55 of paper or the like. Behind the paper there is provided a sheet 57 of a thin metal foil, such as aluminum foil, and behind this there is provided a sheet 58 of cardboard or other relatively soft electrical insulating material which will be readily pierced by the metal point of a dart. The next layer at the rear of the sheet 58 is formed by a central circle 60 and a series of concentric flat circular bands 61 corresponding closely in size and position to the bull's-eye 53 and target bands 54 respectively.

These parts 60 and 61 are formed of a thin metal foil, such as aluminum foil, and as best shown in Fig. 10, they are slightly spaced from one another throughout their entire perimeters. Behind the parts 60 and 61 there is provided a layer 63 of cardboard or other relatively soft electrical insulating material, this layer preferably being of sufficient thickness to prevent complete penetration by a dart. It will be understood that the thickness of the paper 55 and of the metal foil is necessarily greatly exaggerated in Fig. 8. Each of the metal foil bodies is connected by a suitable electrical conductor to a contact on the rear surface of the cardboard layer 63. For this purpose I may use narrow strips of metal foil which pass through slits in the cardboard 63. While these strips may be integral with the foil bodies, they are preferably made from separate pieces. As shown, a foil strip 65 is connected to the central foil member 60, and a separate foil strip 66 is connected to each of the foil members 61. Also, a foil strip 67 is connected to the foil sheet 57. These various strips provide a horizontal row of contacts on the rear face of the target panel and in position to register at assembly with the spring contacts 38, 39 and 40 within the frame 15. The several layers forming the target panel 23 may be held together by a suitable adhesive to provide a unitary structure.

In Fig. 11 there is shown a slightly modified construction for the target panel, in which the foil sheet 57 is placed directly behind the cardboard layer 58 (instead of in front thereof), while the foil members 60 and 61 are placed directly in front of the layer 58 (instead of behind the same). In other words, the positions of the sheet 57, on the one hand, and of the members 60 and 61, on the other hand, have simply been exchanged. This construction requires that narrow openings 70 be provided in the foil sheet 57, so that the strips 65 and 66 may pass therethrough without making contact with the sheet.

In Fig. 12 there is shown a dart of a suitable construction for use with my target. This dart comprises an elongated body 72 of wood or the like, a sharp metal point 73 at the front end of the body, and guide feathers 74 at the rear end of the body.

While certain parts have been described as formed of metal foil, which is the preferred construction, other thin metal structures of an equivalent nature may be employed. For example, it would be feasible to use a fine mesh wire screen instead of metal foil. The invention merely requires a sheet which will conduct electricity and which is readily penetrated by the metal point 73 of the dart, so that the dart may complete an electrical circuit and energize the proper signal.

The operation of the invention will now be apparent from the above disclosure. With the panels 21 and 23 in place within the frame 15, the contacts 66 on the rear of the target panel 23 will respectively engage the spring contacts 38, while the contacts 65 and 67 will respectively engage the spring contacts 39 and 40. The darts will be thrown into the target panel 23 from a suitable distance, and as each dart strikes one of the target areas 53 or 54, the metal point 73 of the dart will penetrate sufficiently to establish an electrical contact between the foil sheet 57 and the particular foil member 60 or 61 which corresponds to the pierced target area. Thus, if the dart registers a bull's-eye in the area 53, the dart point will form an electrical contact between

the foil parts 60 and 57. This will complete a circuit from the batteries 49 through the contact 51, the plate 20, the terminal 36, the buzzer 35, the terminal 43, the wire 44, the spring contact 39, the panel contact 65, the foil part 60, the dart point 73, the foil sheet 57, the panel contact 67, the spring contact 40, the wire 46, the spring contact 47, and thus back to the batteries 49. The resultant current flow will actuate the buzzer 35. If the dart enters one of the annular target areas 54 (say the one marked "5"), it will form an electrical contact between the corresponding foil part 61 and the foil sheet 57. This will complete a circuit from the batteries 49 through the contact 51, the plate 20, one ear 31, the corresponding bulb 30, contact 32, wire 42, spring contact 38, and panel contact 66, the pierced foil part 61, the dart point 73, the foil sheet 57, the panel contact 67, the spring contact 40, the wire 46, the spring contact 47, and thus back to the batteries 49. The resultant current flow will light the bulb 30 behind the numeral "5" in the panel 21, the light being reflected from the back plate 20, as well as from the metal wall 34, so that it will be clearly evident to the participants in the game just what score has been made. The frame member 26 engages the rear surface of the target panel and supports it firmly against the shock of each dart as it strikes the panel. This prevents the impact of the darts from shaking previously thrown darts from the panel.

The target panel 23 is comparatively simple and inexpensive to manufacture, and includes nothing which can injure the points of the darts. There are no permanent electrical wiring connections between the panel and the indicating devices. Consequently when a panel becomes badly worn from long use, it may be easily withdrawn through the slot 25 and replaced by a new panel. The space behind the target panel provides a very convenient place to store the darts when not in use. The sliding panels provide ready access to the batteries and bulbs to facilitate replacement when necessary.

Having thus described my invention, what I claim as new and desire to secure by Letters Patent is:

1. A target for darts or the like comprising a frame, a target panel mounted on the frame and readily removable therefrom, the panel including two thin metal structures separated by electrical insulating material and arranged to be pierced and electrically connected by the metal point of a dart, an electric signal mounted on the frame, two contacts mounted on the frame and in circuit with the signal, and two contacts on the panel electrically connected to the respective metal structures, the panel contacts engaging the respective frame contacts automatically upon mounting the panel on the frame.

2. A target for darts or the like comprising a frame, a target panel mounted on the frame and readily removable therefrom, the panel including two thin metal structures separated by electrical insulating material and arranged to be pierced and electrically connected by the metal point of a dart, an electric signal mounted on the frame, two yieldable spring contacts on the frame and in circuit with the signal, and two contacts on the panel electrically connected to the respective metal structures, the panel contacts engaging the respective spring contacts automatically upon mounting the panel on the frame.

3. A target for darts or the like comprising a frame having grooves, a flat target panel ar-

ranged to slide edgewise into position in the frame with the edges of the panel engaging the grooves, the panel including two thin metal structures separated by electrical insulating material and arranged to be pierced and electrically connected by the metal point of a dart, an electric signal mounted on the frame, two yieldable spring contacts mounted on the frame and in circuit with the signal, and two contacts on the rear surface of the panel electrically connected to the respective metal structures, the panel contacts engaging the respective spring contacts automatically as the panel slides into place in the frame.

4. A target for darts or the like comprising a frame, a flat target panel mounted on the frame and readily removable therefrom, the front face of the panel being marked to designate a plurality of target areas, the panel including two layers of thin metal separated by electrical insulating material, one layer being divided into a plurality of electrically insulated parts corresponding in shape and position to the respective target areas and the other layer being continuous throughout all the target areas, the construction being such that the metal point of a dart thrown into a given target area will pierce and electrically connect the corresponding metal layer part with the continuous metal layer, a plurality of electric signals mounted on the frame, a contact mounted on the frame and common to all the signals, a plurality of additional contacts mounted on the frame and in circuit with the respective signals, a contact on the panel electrically connected to the continuous metal layer and arranged to engage the said common contact automatically as the panel is placed in the frame, and a plurality of contacts on the panel electrically connected respectively to the parts of the said divided layer and arranged to engage respectively the said additional contacts automatically as the panel is placed in the frame.

5. A target for darts or the like comprising a frame, a flat target panel mounted on the frame and readily removable therefrom, the front face of the panel being marked to designate a central circular bull's-eye surrounded by substantially contiguous circular bands to form definite target areas, the panel including two layers of thin metal separated by electrical insulating material, one layer being divided into a plurality of slightly separated parts corresponding in shape and position to the respective target areas and the other layer being continuous throughout all the target areas, the construction being such that the metal point of a dart thrown into a given target area will pierce and electrically connect the corresponding metal layer part with the continuous metal layer, a plurality of electric signals mounted on the frame, a contact mounted on the frame and common to all the signals, a plurality of additional contacts mounted on the frame and in circuit with the respective signals, a contact on the panel electrically connected to the continuous metal layer and arranged to engage the said common contact automatically as the panel is placed in the frame, and a plurality of contacts on the panel electrically connected respectively to the parts of the said divided layer and arranged to engage respectively the said additional contacts automatically as the panel is placed in the frame.

6. A target for darts or the like comprising a frame, a plate of sheet metal secured to the rear of the frame, a target panel mounted on the front of the frame and including two thin metal

structures separated by electrical insulating material and arranged to be pierced and electrically connected by the metal point of a dart, and an electric signal connected in a circuit with the said metal structures, the sheet metal plate forming a portion of the said circuit.

7. A target for darts or the like comprising a frame, a plate of sheet metal secured to the rear of the frame, an ear struck up from the said sheet and shaped to provide a socket, an electric lamp bulb mounted in the socket, a target panel mounted on the front of the frame and including two thin metal structures separated by electrical insulating material and arranged to be pierced and electrically connected by the metal point of a dart, and means connecting the lamp bulb in a circuit with the said metal structures, the sheet metal plate and ear forming a portion of the said circuit.

8. As an article of manufacture, a target panel for an electrically indicating target for darts or the like in the form of a laminated structure comprising a comparatively thick rear layer of relatively soft electrical insulating material, a layer of thin metal in front of the rear layer, a layer of relatively soft electrical insulating material in front of the metal layer, a layer of thin metal in front of the last mentioned insulating layer, a thin front layer of paper or the like marked to indicate definite target areas, one of the metal layers being divided into separate parts corresponding in shape and position to the respective target areas, a plurality of contacts on the rear surface of the said thick rear layer electrically connected respectively to the parts of the divided metal layer, and a contact on the rear surface of the said thick rear layer electrically connected to the other metal layer, all the said layers being fastened to one another to provide a unitary structure, and the metal layers

being such as to be readily pierced and electrically connected by the metal point of a dart.

9. As an article of manufacture, a target panel for an electrically indicating target for darts or the like in the form of a laminated structure comprising a comparatively thick rear layer of relatively soft electrical insulating material, a layer of thin metal in front of the rear layer, a layer of relatively soft electrical insulating material in 10 front of the metal layer, a layer of thin metal in front of the last mentioned insulating layer, a thin front layer of paper or the like marked to indicate definite target areas, one of the metal layers being divided into separate parts corresponding in shape and position to the respective target areas, a plurality of contacts on the panel electrically connected respectively to the parts of the divided metal layer, and a contact on the panel electrically connected to the other metal layer, all the said layers being fastened to one another to provide a unitary structure, and the metal layers being such as to be readily pierced and electrically connected by the metal point of a dart.
